DESIGN FOR A DRESS

Irving A. Winter, New York, N. Y.

Application April 6, 1937, Serial No. 68,578

Term of patent 3½ years

To all whom it may concern:

Be it known that I, Irving A Winter, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein.

The characteristic feature of my design resides in the collar portion of the blouse, in combination with the gored skirt of the dress, as shown.

I claim:

The ornamental design for a dress, substantially as shown, and described.

IRVING A. WINTER.
